UNITED STATES PATENT OFFICE.

ISAAC W. HUMPHREY AND HARRY A. SPURGEON, OF DAYTON, OHIO.

TOY FLYING-MACHINE.

970,829.

Specification of Letters Patent. Patented Sept. 20, 1910.

Application filed February 19, 1910. Serial No. 544,761.

To all whom it may concern:

Be it known that we, ISAAC W. HUMPHREY and HARRY A. SPURGEON, citizens of the United States, residing at Dayton, in the county of Montgomery and State of Ohio, have invented certain new and useful Improvements in Toy Flying-Machines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to new and useful improvements in toy aeroplanes.

The object of the invention is to provide a toy of the above description which may be constructed at a minimum cost and which possesses the novel and advantageous features hereinafter described in the specification and pointed out in the claim.

In the accompanying drawings, Figure 1 is a perspective view of our improved toy aeroplane. Fig. 2 is a side elevation of the same. Fig. 3 is a top plan view of the motor frame.

In the specification and drawings, similar reference characters indicate corresponding parts.

1—1 designates upper and lower supporting planes which are held apart by means of two end braces 2—2 and intermediate side marginal braces 3—3. The planes 1—1 are constructed of thin tenacious paper or any other suitable material which is held taut or in shape by a light framework 4 preferably made of ratan. The braces 3—3 are attached directly to the frame-work 4, and the intermediate portions of the frame are reinforced as at 5 to strengthen them at such points. Mounted on the forward intermediate braces 3—3 is a propeller shaft block 6 from which rearwardly extend members 7 which constitute the frame work of the motor. The members 7 are attached to the rear braces 3—3 and the said members at their rear ends support the rear planes 8—8 which are of areas approximately one fourth the area of the front planes 1—1. The rear planes 8—8 are constructed in a manner similar to the front planes 1—1 and the same consist of ratan frames 9 and upright braces 10 and 11. The rear intermediate braces 11 pass tightly through the extreme

rear ends of the members 7 constituting the motor frame while the forward intermediate braces 11 pass somewhat loosely through the motor frame members 7. At the junction of the motor frame members 7 and the rear intermediate braces 11, is mounted a block 12 which supports a pin 13. Passing around the pin 13 is an endless rubber band 14 which is attached at its opposite end to a loop or eye 15 on the inner end of the propeller shaft 16 which is journaled in the block 6. This elastic band 14 constitutes the motor which drives the propeller 17, the latter being mounted upon the end of the shaft 16. When it is desired to fly the machine, the propeller 17 is rotated by the fingers in a direction opposite to that which propels the machine forward, and until sufficient energy is stored in the motor or elastic band 14 to drive the propeller. The machine is then released or thrown into the air and is caused to soar or fly under the influence of the revolving propeller. From Fig. 2 it will be noted that the longitudinal members 7 constituting the motor frame, curve downwardly and to some extent offer the least resistance thereby to the upward movement of the toy. The rear planes 8—8 may be shifted to vary their angles up or down relatively to the planes of the forward sustaining members 1—1. This may be done by pressing upwardly or downwardly the front portions of the rear planes 8—8, it having been stated that the forward intermediate braces 11 of said planes are sufficiently loose where they pass through the frame members 7, to permit of such changing of the angle of said planes. The propeller blades 17 are comparatively light being constructed preferably of aluminum, and the device as a whole is exceedingly light owing to the material from which it is constructed.

We claim:

A toy of the type specified comprising a downwardly curved motor frame extending the length of the device and constituting the main frame, a propeller supported on the forward end of said frame, an elastic motor having one end connected to the shaft of said propeller and the other end connected to the tail-piece of the motor frame, two forwardly disposed planes held apart by end braces and supported on the motor frame by intermediate braces, and two rearward planes having areas approximately one

2
fourth of the areas of the front planes, said rearward planes being held apart by end braces and supported on the motor frame by intermediate braces engaging the motor frame and the tail-piece of the motor frame, said rear planes being adapted to be varied in their angles relative to the front planes, as herein shown and described.

In testimony whereof we affix our signatures, in presence of two witnesses.

ISAAC W. HUMPHREY.
HARRY A. SPURGEON.
